Application January 4, 1957, Serial No. 632,516

Claims priority, application Great Britain
January 13, 1956

4 Claims. (Cl. 1—6)

This invention relates to nail distributors of the general type disclosed in United States Letters Patent No. 2,604,624 which was granted July 29, 1952 on an application filed in the names of Wallace M. Cutler et al. and which discloses a carrier having a plurality of nailways mounted for horizontal vibration in a fixed frame, an eccentric which is mounted for vibrating movement in the carrier and the throw of which may be varied, and an inertia device through which the vibrations of the eccentric are imparted to the carrier.

It is an object of the present invention to provide an improved nail distributor of the type above referred to. The present invention consists in improved stops for limiting movement of nails down nailways of the carrier when leading nails resting partly in said nailways and partly in passages of a nail roll, which is rotatable in the carrier, are being dumped from the nailways. This invention also consists in improved stops for orienting leading double-pointed nails, which are in the passages of the nail roll and rest partly in the lower ends of the nailways, about their axes, said stop also serving to limit movement of said double-pointed nails along said passages and nailways. The present invention further consists in novel features hereinafter described, reference being had to the accompanying drawings which illustrate embodiments of the invention selected for purposes of illustration, said invention being fully disclosed in the following description and claims.

In the accompanying drawings,

Fig. 1 is a view showing the upper portion of the nail distributor in said elevation and the lower portion of the distributor in vertical longitudinal section as viewed from just inside a right side cover plate of the machine;

Fig. 2 is a plan view, partly broken away, of the distributor;

Fig. 3 shows, partly in side elevation and partly in section on the line III—III of Fig. 4, a frictional arrangement which is adapted to control the amount of vibration of a nail carrier of the distributor and which may be substituted for a similar friction arrangement illustrated in Figs. 1 and 2;

Fig. 4 is a view on the line IV—IV of Fig. 3;

Fig. 5 shows in plan a stop bar which may be substituted for a corresponding stop bar of the nail distributor illustrated in Figs. 1 and 2 in order to equip said distributor for accommodating nails which are pointed at their opposite ends and are disclosed in United States Letters Patent No. 2,768,379, granted October 30, 1956 on an application filed in the name of Lawrence Mawbey; and

Fig. 6 is a section on the line VI—VI of Fig. 2 showing two rotatable unbalanced shafts which are mounted in and effect vibration of the nail carrier.

The illustrative nail distributor comprises a main frame 20 which is adapted to be secured to a main frame (not shown) of a wood heel nailing machine, for example, and

2

which has an upwardly extending rear portion to which the upper ends of rear leaf springs 22 are secured by screws 24. The lower ends of the leaf springs 22 are secured by screws 25 to a rear portion of a carrier 26 having upper and lower nailways 28, 28a respectively which are substantially identical with nailways disclosed in said Patent No. 2,604,624. The carrier 26 has secured to its front end a depending bracket 26a the lower end of which has secured to it by screws 30 the lower end portions of front leaf springs 32 which are secured at their upper ends to the main frame 20 by screws 34. It will thus be apparent that the carrier 26 and accordingly the upper and lower nailways 28, 28a are supported for horizontal reciprocation or vibration generally lengthwise of the nailways, excessive movement of the carrier on the leaf springs 22, 32 being prevented by dampening means hereinafter described.

Journalized for rotation in ball bearings mounted in the carrier 26 are identical upper and lower shafts 36, 38 having unbalanced weighted portions 36a, 38a respectively the centers of gravity of which are arranged equal distances from axes of rotation 40, 42 respectively of the shafts. Secured to the upper and lower shafts 36, 38 are identical fibre pinions 44, 46 respectively which are in meshing relation with each other and cause the shafts to rotate in opposite directions at the same speed. The upper and lower shafts 36, 38, which may be defined as weighted unbalanced shafts, are so arranged that during their rotation their centers of gravity or mass are at all times arranged vertically opposite each other, said shafts being offset 180° from each other about their axes respectively. The lower shaft 38 has secured to it a pulley 48 driven by a belt 50 which passes around a drive pulley 52, an idler pulley 54 which is journaled upon a bearing pin 56 mounted upon the main frame 20, and an idler pulley 58 which is journaled on a bearing pin 60 carried by a bar 62 pivoted on a stud 64 secured to the main frame. A tension spring 66 has its upper and lower ends attached respectively to the bar 62 and to the main frame 20 and serves to keep the belt 50 taut. The driving pulley 52 is secured to a shaft 68 which is rotatably mounted in the main frame 20 and has secured to it a worm 70 meshing with a worm wheel 72 which is keyed to a shaft 74 rotatably mounted in said main frame. Secured to the shaft 74 is a grooved wheel 76 which, in cooperation with an idler grooved wheel 78, rotatably supports a drum 80 adapted to hold nails 82 in bulk and to drop them into the upper nail raceways 28. The shaft 68 has at its left end, as viewed from the front of the machine, a pulley 84 by which the shaft may be rotated, the unbalanced weighted shafts 36, 38 preferably being rotated at about 1200 r.p.m.

The construction and arrangement of the unbalanced weighted shafts 36, 38 and the directions of their rotation is such that their simultaneous forward and rear or horizontal components of movement cause, by centrifugal action, the carrier 20 and its nailways 28, 28a, to reciprocate or vibrate horizontally and generally lengthwise of said nailways. The construction and arrangement of the unbalanced weighted shafts 36, 38, which may be referred to as unbalanced weights, is such that the vertical components of unbalanced force of each of the weighted shafts, acting through its center of gravity, is equal to and in an opposite direction from the vertical component of unbalanced force of the other weighted shaft acting through its center of gravity. Accordingly there is little, if any, tendency for the carrier 20 and its nailways 28, 28a to move or vibrate vertically and thus dislodge the nails 82 in said guideways, the construction and speed of the unbalanced shafts 36, 38 being such that the carrier is moved about $\frac{1}{8}$ " to and fro in a horizontal path. The above described arrange-

ment for operating the carrier 20 includes relatively few moving parts and the leaf spring supporting arrangement for the carrier provides a free running arrangement with a little vibration and a minimum amount of noise and wear.

The illustrative distributor may be said to comprise means such, for example, as the unbalanced shafts or weights 36, 38 which are fixedly journaled for rotation in the carrier 26 and which during said rotation have their combined center of gravity reciprocated or vibrated in the carrier harmonically in a path extending generally horizontally or lengthwise of the nailways 28, 28a. The unbalanced weights or shafts 36, 38 may be described as being moved or rotated by power in the carrier 26 in fixed paths, components of centrifugal forces extending generally horizontally or lengthwise of the nailways 28, 28a and produced by movement or rotation of the shafts or weights in the carrier being equal and additive to cause reciprocation or vibration of the carrier horizontally or generally lengthwise of the nailways and components of said forces which extend vertically or heightwise of the nailways and are produced by movement of the shafts or weights in the carrier being equal and opposite and thus insuring against any substantial vertical movement or vibration of the carrier. The axes 40, 42 about which the unbalanced shafts or weights 36, 38 are rotated may be described as being parallel and arranged substantially in a vertical plane or in a plane disposed at substantially right angles to said nailways 28, 28a, the centers of gravity of said shafts or weights during their rotation being arranged in vertical alinement as they are displaced harmonically generally lengthwise of the nailways with relation to the carrier. The nails 82 are delivered head first to a discharge or inverting roll 86 of the carrier 26 said carrier having a gap 88 corresponding to the gap (390) of the nail distributor disclosed in said Patent No. 2,604,624 and having an adjustable balancing bar 90 corresponding to the bar (386) of such distributor. The discharge roll 86 is provided with passages 92 and is similar to the roll (134) disclosed in said Patent No. 2,604,624, the roll being operated by means hereinafter described. The nail distributor also has in front of the discharge roll 86 a nail stop 94 which corresponds to the stop (464) described in said Patent No. 2,604,624 and is adapted to stop lengthwise movement of the nails when they have entered said roll.

The balancing bar 90 extends across the front end of the upper nailways 28 and is slidably mounted along inwardly extending faces 96, 96a of side plates 98, 98a respectively, of the carrier 20. The balancing bar 90 has at each of its lateral portions a forwardly and rearwardly extending row of teeth 100 which are engaged by teeth 102 on a balancing bar adjusting shaft 104 rotatably mounted in the side plates 98, 98a of the carrier 20. The shaft 104 has secured on it a hand wheel 106 by which it may be rotated to adjust the balancing bar 90 toward or from the upper nailway 28 in accordance with the length of the nails being used. Between the hand wheel 106 and the adjacent side plate 98 of the carrier is a spring 108 which frictionally prevents movement of the balancing bar 90 from its adjusted position.

Mounted upon the carrier 26 are a plurality of aligned spring fingers or nail stops 110, one for each of the lower raceways 28a. The forward portions of the fingers 110 are arranged to be moved into engagement with nails 82 next to those nails which have passed into the passages 92 of the discharge roll to hold such nails from moving along the lower nailways while the nails in the roll are being discharged. The spring fingers 110 are secured on a shaft 112 rotatably mounted in bearing blocks 114 which are slidably mounted in guideways 116 of the side plates 98, 98a of the carrier 26. Outer upper faces of the blocks 114 are provided with rack teeth 118 which are engaged by gear teeth 120 formed

on an adjusting shaft 122 rotatably mounted in the side plates 98, 98a of the carrier 26. The shaft 122 has secured to it a hand wheel 124 by which the shaft may be rotated and the spring fingers or stops 110 initially adjusted toward and away from the discharge roll 86 or lengthwise of the lower nailways 28a in accordance with the length of the nails 82 being handled. The spring fingers or stops 110 may be described as being movable between projected positions in which they prevent movement of the nails down the lower nailways 28a and retracted positions in which they allow the nails to move down said nailways into the discharge roll 86.

The shaft 112 has secured to its right-hand end an arm 126 which has fixed to it a pin 128 engaging in a slot 130 in a lever 132 supported by parallel links 134 pivoted for vertical movement on bearing studs of the carrier. The lever 132 is operatively connected by a pin 136 to the lower link 134 and to the rear portion of a lever 138 the forward end portion of which has formed in it a slot 140 which is engaged by a pin 142 carried by an arm 144 secured to the discharge roll 86. The lever 138 has pivoted to it, nearer to the pin 136 than to the slot 140, the upper portion of a link 146 a lower end portion of which is pivoted to an arm 148 secured to a shaft 150 rotatably mounted in the side plate 98 of the carrier 26. Also secured to the shaft 150 is an arm 152 to which is pivoted the upper end of a rod 154. The arm 148 is constantly urged clockwise, as viewed in Fig. 1, by a tension spring 156 the lower end of which is attached to the main frame 20. The spring 156 normally retains the lever 132 against a pin 158 secured to the side plate 98 of the carrier 26, the spring fingers 110 in their raised or retracted positions, and the discharge roll 86 in a position in which the passages 92 of the roll are aligned with the lower nailways 28a for receiving nails from the nailways, this position of the roll being adjustable by the use of a screw 160 which is threaded into a lug of the arm 144 and is normally held by the spring 156 in engagement with a lug 162 of the carrier 26. The construction is such that when the rod 154 is lowered the spring fingers 110 are moved to their projected positions into engagement with the second line of nails in the lower nailways 28a before the discharge roll 86 is rotated to deliver nails in the passages 92 thereof into a conduit 164, hereinafter referred to, and when the rod is raised, the spring fingers and the discharge roll return to their retracted positions.

The rod 154 may be connected to a part of the heel attaching machine with which the illustrative distributor is being used, the arrangement being such that the distributor delivers the nails 82 to a loader block (not shown) of the machine at a suitable time which may be during actual operation of the machine or between successive operations thereof. If desirable, the rod 154 may be connected to a manually actuated lever or treadle (not shown).

The left end portion of the nail discharge roll 86, as viewed from the front of the machine, has a reduced threaded portion on which is threaded a collar 166 arranged to be locked in adjusted position by a locknut 168, said collar being cut away to form a channel adapted to be engaged by a rear arm of a hand lever 170 pivoted on a bearing screw 172 secured to the side plate 98a of the carrier 26. The front arm of the hand lever 170 has formed on it a thumb piece 174 by depression of which the rear arm of the lever may be raised out of the channel against the action of a spring 176 opposite ends of which are connected respectively to the rear arm of the lever and to the side plate 98a of the carrier and which normally holds said rear arm in engagement with the channel. With the lever 170 in engagement with the channel in the collar 166, and the locknut 168 slackened, the collar may be rotated to adjust the discharge roll 86 lengthwise, bringing the nail receiving passages 92 thereof into alinement with associated lower nail-

ways 28a. When the rear arm of the lever 170 has been raised out of the channel in the collar 166 the discharge roll 86 may be withdrawn from the apparatus and another roll having a different number or size of nail receiving passages may be substituted therefor.

The aforesaid nail stop 94 in front of the discharge roll 86 comprises a bar 178 which has a planar nail engaging face 180 and is slidably mounted on guideways 182 of the side plates 98, 98a respectively of the carrier 26. The lateral end portions of the bar 178 are provided with rack teeth 184 which are engaged by gear teeth 186 on a shaft 188 rotatably mounted in the side plates 98, 98a of the carrier 26. The shaft 188 has secured on it a hand wheel 190 by which it may be rotated to adjust the bar 178 forwardly and rearwardly along the guideways 182 in accordance with the length of the nails being used.

The rear face of the bar 178 is usually planar, as above explained, but if nails 192 (Fig. 5), which have a point 194 and a bevel face 196 at each of their ends and are disclosed in said Patent No. 2,768,379, are to be handled in the distributor there may be provided in place of said bar a bar 198 having extending inwardly from its rear face a series of recesses 200 (one for each raceway) extending from the top to the bottom of the bar. Each recess 200 has a planar side face 202 which is inclined to a planar end face 204 of the recess, said side faces being arranged at such an angle to the path of movement of the nails as they travel down the lower nailways 28a and through the passages 92 that they are engaged by bevel faces 196 of the nails and the nails are so oriented that their bevel faces are arranged vertically. The nails 192 which follow the leading nails in the lower nailways 28a are oriented into positions in which their bevel faces 196 are vertically arranged by reason of the engagement of their forward ends with the rear ends of the leading nails and are thus prevented from overriding the leading nails. The planar side face 202 of each of the recesses 200 may be defined as being vertical (that is plumb) and as positioned adjacent to and arranged opposite the exit end of an associated passage 92 of the inverting roll 86 in its nail receiving position, and as being inclined at a slight angle to an axis of the associated passage 92.

The nails 82 or 192, as they drop from the nail discharge roll 86, fall down the conduits 164 and into flexible tubes 206 to a foot plate (not shown) from which they are transferred as a "gang" to a nailing die (not shown) of the heel attaching machine by a loader block (not shown). The conduits 164 are formed by a bracket 208 which is secured to the front of the main frame 20 of the distributor and a cover 210 pivoted to said bracket. The bracket 208 has secured to it a bar 212 which has extending into its front end a number of recesses (not shown) spaced apart by distances equal to the distances respectively between the lower nailways 28a. Supported in the recesses of the bar 212 are the tubes 206 each of which has at its upper end a flange resting on a suitably formed step of an associated recess. The tubes 206 are held in the recesses of the bar 212 by a coil spring 214 which extends across the tubes and opposite ends of which are attached to the bar. The cover 210 which is pivotally mounted at 216 to the bracket 208 is held against the bracket by threaded bolts 218 pivoted on said bracket and extending through notches 220 in the ends respectively of the cover. When hand nuts 222 threaded onto the bolts 218 have been loosened the bolts may be swung out of the notches 220 in the cover 210 and said cover may be then swung rearwardly to give access to the conduits 164. The conduits 164, which are formed between the bracket 208 and the cover 210, taper downwardly from the upper ends, said upper ends being oblong in shape with rounded ends and lower ends of the conduits having the form of round holes.

Because of the manner in which the carrier 26 and its driving mechanism are supported by the leaf springs 22, 32 excessive horizontal to and fro movements of the carrier are likely to occur if the normal to and fro movements of said carrier caused by its driving mechanism are interrupted, for example, by undue vibrations of the heel attaching machine or by reason of the carrier being engaged by a foreign object. To overcome these excessive vibrations and return the to and fro movement of the carrier 26 to normal there is provided the hereinafter described dampening device which comprises U-shaped blocks 224 (Fig. 2) secured respectively to the side plates 98, 98a of the carrier 26. Each block 224 has formed in it a forwardly and rearwardly extending slot or bore 226 through which extends a bolt 228 which has a head and has slidably mounted on it a collar 230. The collar 230 and the head of the bolt 228 are compressed against opposing surfaces of the block 224 by a spring 232 which is mounted on the bolt and opposite ends of which engage respectively the collar and a nut 234 threaded onto the bolt. Mounted at opposite sides of the main frame 20 for fore and aft adjustment are brackets 236 each having a pair of opposed parallel stop faces or stops 238. The bolt 228, the collar 230, the spring 232 and the nut 234 may be said to constitute a slide unit. Each of the brackets 236 has a threaded bore for receiving a screw 240 (Fig. 1) passing through a slot 242 in the main frame 20 and threaded into the bracket are a pair of elongated adjusting screws 244, the construction being such that the brackets may be initially set in different adjusted positions on the frame 20 with the stop faces 238 arranged in vertical relation. The brackets 236 are so set in the main frame 20 that there is just room for the collar 230 to move with the carrier 26, as it moves normally to and fro, without touching the faces 238. Should the amplitude of vibration of the carrier 26 become excessive the collar 230 will engage first one and then the other of the stop faces 238 of the brackets 236 and its movement will be stopped thereby, frictional engagement of the collar and the head of the bolt 228 with the bracket 224 tending to slow down or reduce the movement of the carrier. Such action will continue until the carrier 26 once more moves normally to and fro. The frictional engagement of the collars 230 with the brackets 224 is effective in slowing down the carrier 26 as it moves in both directions and since there is little room for movement of the collar 230 between the faces 238 of the brackets 236 the return of the carrier to normal is comparatively quick.

Another design for overcoming excessive vibrations of the carrier 26 is shown in Figs. 3 and 4 and comprises a bracket or stop 246 secured by screws 248 to the rear of the main frame 20. The bracket 246 has a slot or bore 250 for receiving a collar or dampener 252 which is provided with a flanged portion 254 adapted to engage the bracket and which has mounted slidably on it a friction ring 256. The flange portion 254 of the collar 252 and the friction ring 256 are pressed against the bracket by a spring 258 opposite ends of which are in engagement respectively with the friction ring and a washer 260 secured to the collar by a screw 262. Secured to and forming part of the carrier 26 is a bracket 264 having a depending pin or projection 266 which extends into a recess 268 formed in the collar 252. The recess 268 is about $\frac{1}{8}$ " larger than the diameter of the pin 266 and allows said pin to move to and fro with the carrier 26 during its to and fro movements without touching the sides of the recess. Should the carrier 26, however, set up excessive vibration the arrangement operates in a similar manner as that described to bring the to and fro movements of the carrier 26 back to normal.

The bolt 228 and the collar 230 on the one hand and the collar 252 and the friction ring 256 on the other hand may be defined as friction means adapted to be carried by the carrier 26 to regulate the amount of vibra-

tion of the carrier, and the U-shaped blocks 224 and the brackets 246 may be described as having cylindrical bores defined by cylindrical surfaces shaped and arranged for engagement with the friction means to limit the amount of vibration of the carrier. The dampening means for controlling the amplitude of vibration of the carrier 26 may be described as being adapted to bear frictionally on the carrier or as comprising friction means for dampening or limiting the amount of vibration of the carrier in opposite directions, and means for positively limiting the amount of vibration of the carrier in said opposite directions.

The dampening device may also be described as comprising a slide unit adapted to allow the carrier 26 to be freely moved or vibrated a predetermined distance in opposite directions and to be resistingly moved by the carrier when the carrier is moved in said opposite directions a distance greater than said predetermined distance, stops formed by opposite ends of the slot 250 being provided for positively limiting movement of the slide unit in said opposite directions. The modified slide unit shown in Figs. 3 and 4 includes the spring actuated friction ring 256 which is adapted to cause this slide unit to be pressed against the frame 246 and accordingly yieldingly to resist movement of the carrier 26 when said carrier is reciprocated in said opposite directions a distance greater than said predetermined distance. The modified dampening means shown in Figs. 3 and 4 may also be defined as having a recess 268 of suitable size to receive the projection 266 of the carrier 26 and to allow a predetermined amount of vibration of said projection in the recess without meeting resistance. The friction ring 256 may also be said to cause the collar 252 to resist movement of the projection 266 and accordingly the carrier when the vibration of the carrier becomes greater than a predetermined amount.

Having thus described our invention, what we claim as new and desire to secure by Letters Patent of the United States is:

1. In a nail distributor, a carrier having nailways, means for vibrating said carrier generally lengthwise of said nailways, a roll for receiving nails delivered by the nailways, stops which are mounted for movement between projected positions in which they prevent movement of nails down said nailways and retracted positions in which they allow the nails to move down the nailways to said roll, mechanism for moving the stops from their retracted to their projected positions, mechanism for rotating said roll to dump nails therefrom, means for operating said first- and second-named mechanisms in sequence whereby to operate said stops and thereafter to operate said roll, and means for initially adjusting said stops into different operative positions generally lengthwise of the nailways.

2. In a nail distributor, a carrier having nailways, means for vibrating said carrier generally lengthwise of the nailways, a discharge roll for receiving nails from the nailways, bearing blocks which are mounted in the carrier, a shaft pivotally mounted in the bearing blocks, stops which are secured to said shaft and are movable

5
10

between retracted positions in which they are spaced substantial distances from the nailways to allow the nails to move down said nailways for reception by said roll and projected positions in which they prevent movement of the nails down the nailways, means for operating said shaft to move the stops from their retracted to their projected positions whereby to retain the nails against movement on the nailways, and for thereafter rotating the roll to dump nails from said roll, and means for initially moving the bearing blocks into different adjusted positions in the carrier to move said stops into different operative positions lengthwise of the nailways.

3. In a nail distributor, a carrier having a nailway, a discharge member provided with a cylindrical passage which has entrance and exit ends and is adapted to receive from the nailway a double pointed nail having beveled ends, means for moving said member between nail receiving and nail discharging positions, and a nail stop having a vertical face which is positioned adjacent to and opposite the exit end of said cylindrical passage when said passage of said member is in its nail receiving position and which is inclined at a slight angle to an axis of said passage, said face being adapted to be engaged by the leading beveled ends of the nails delivered into the passage of said member and to orient said nails about their axes as well as to position the nails lengthwise in said passage.

4. In a nail distributor, a carrier having nailways, means for vibrating the carrier to cause double pointed nails having beveled ends to move along the nailways to exit ends thereof, a discharge roll having passages provided with entrance and exit ends, means for moving the roll between a nail receiving position in which said passages are in alignment with the exit ends of the nailways and a nail discharging position in which the nails are dumped from the roll, and a nail stop positioned adjacent to the exit end of the discharge roll and having a nail receiving end provided with a plurality of recesses side faces of which are vertically disposed and are inclined with relation to lengthwise dimensions of said passages when the roll is in its nail receiving position, said faces being adapted to be engaged by the leading ends of the nails in the passages of the roll whereby to limit movement of said nails in said passages and to orient the nails in said passages about their axes respectively to positions in which the beveled ends of the nails are vertically arranged.
